UNITED STATES PATENT OFFICE.

JAMES C. DAWSON, OF ST. LOUIS, MISSOURI, ASSIGNOR TO SIEBER & TRUSSELL MANUFACTURING COMPANY, A CORPORATION OF MISSOURI.

LOOSE-LEAF BINDER.

No. 873,417.

Specification of Letters Patent.

Patented Dec. 10, 1907.

Application filed April 29, 1907. Serial No. 370,906.

To all whom it may concern:

Be it known that I, JAMES C. DAWSON, a citizen of the United States, and resident of the city of St. Louis, State of Missouri, have invented certain new and useful Improvements in Loose-Leaf Binders, of which the following is a specification, and which are illustrated in the accompanying drawings, forming a part thereof.

10 The invention relates to loose leaf binders comprising a hinged metal frame adapted to be secured within the back section of a holder of book form, the parts of the frame being provided with oppositely - directed filing 15 prongs.

The object of the invention is to simplify and improve the construction of binders of this type; and the invention is exemplified in the structure to be hereinafter described 20 and illustrated in the accompanying drawings, in which

Figure 1 is a plan view of a binder frame embodying the invention, the parts of the frame being in the closed position; Fig. 2 is a 25 transverse sectional view of the same; Fig. 3 is a perspective view illustrating a detail of the construction; Fig. 4 is a sectional view showing the binder frame open; and Fig. 5 is an end view of the frame when closed. Fig. 30 6 is a detail of one of the binder plates with the filing prong removed.

A pair of metal plates 10 and 11, of angular section but having a rounded corner 12, form the sides and back of the binder, each of 35 the plates preferably having an integral inwardly turned end flange 13. The plates 10 and 11 are hinged together, as by pivots 14, 15, which unite the flanges 13 at each end, and one or more catches 16 are provided for locking 40 the parts of the binder in the closed position.

As shown, such a catch is provided at each end of the binder. Each catch comprises a headed stud 17, carried by a spring plate 18 secured by clips 29 to the end flange 13 of one of the plates 10 and 11, the shank of the stud being enlarged at 19 adjacent its base. The adjacent end flange 13 of the other plate is provided with a T-slot 20 to receive the stud 50 17, the throat of the slot being only of sufficient width to permit the passage through it of that part of the shank of the stud 17 which is of reduced diameter. That part of the flange 13 which forms the margins of the 55 throat of the slot 20 is flanged upwardly, as

indicated at 21, 22, to engage the base 19 of the shank of the stud 20 by a cam action when the binder is closed to depress the stud.

Sheet-receiving prongs 23, which extend inwardly across the binder frame, are carried by each of the plates 10 and 11. As shown, these prongs are curved to cross the frame in the form of an arch, and each is of such length that it extends from one of the plates 10, 11, into engagement with an aperture 24 provided in the other plate for receiving the free end of the prong, when the binder is closed.

The prongs 23 are secured to the frame members of the binder in the following way: 70 The plates 10, 11, are provided with slotted apertures 25 for receiving the body of the prong, and clamping lugs 26, 27, are turned outwardly from the plate adjacent such apertures. Each of the prongs 23 has a flattened heel 28, which is seated upon the outer face of the plate, as 10, 11, between the lugs 26, 27, the body of the prong extending inwardly through the aperture 25, its curved form giving it a direction which is inclined to 75 the plate and thus causing it to fill the slotted aperture. By clinching the lugs 26, 27, onto the heel 28 of the prong, an exceedingly secure fastening is obtained without the use of solder, the use of solder being objectionable 80 as it interferes with the subsequent plating of the parts.

If desired covers (not shown) may be provided for the binder. They may be attached to the binder in any convenient way, as by 90 riveting to the side plates 10 and 11. Preferably the structure of the binder frame will be stiffened by providing upon the ends of each of the plates 10, 11, a lip 30, to be overturned upon the adjacent end flange 13, this 95 flange being thus clamped between the lip and the end of the plate against which it is seated, as shown at 31.

I claim as my invention—

1. In a binder, in combination, a pair of 100 relatively movable side plates, each of such plates having a prong-receiving aperture, a pair of clamping lugs turned outwardly on one of the plates adjacent the aperture, and a filing prong having a flattened heel, such 105 prong extending inwardly through the aperture in the last-named plate and having its heel seated upon the outer face of such plate between the clamping lugs, the end of the prong being engageable with the aperture in 110

- the other plate and the clamping lugs being clenched upon the heel of the prong.
2. In a binder, in combination, a pair of relatively movable side plates, one of such plates having an aperture elongated in a direction transverse to the length of the plate, a clamping lug turned outwardly on the plate adjacent the aperture, and a filing prong having a flattened heel, the prong being extended inwardly through the aperture in the plate and being inclined to the plate to fill the aperture, the heel of the prong being seated upon the outer face of the plate and being held to its seat by clenching the lug.
- 15 3. In a binder, in combination, a binder plate in angle form, an end flange integral with one leaf of the plate and filling the angle between the leaves, and a lip integral with the other leaf of the plate and engaging the flange.

4. In a binder, in combination, an apertured binder plate, a filing prong set through the aperture, and means for clamping the heel of the prong against the rear face of the plate.

25 5. In a binder, in combination, an apertured binder plate, a filing prong set through the aperture, and a pair of clamping lugs engaging the heel of the prong and binding it to the plate.

6. In a binder, in combination, an apertured binding plate, a filing prong having a flattened heel and projecting through the aperture, and a clamping lug on the plate and engaging the flattened portion of the prong. 35

JAMES C. DAWSON.
